UNITED STATES PATENT OFFICE.

VINCENT BENDIX, OF CHICAGO, ILLINOIS.

ENGINE-STARTER.

1,327,303.

Specification of Letters Patent.

Patented Jan. 6, 1920.

Application filed March 31, 1919. Serial No. 286,386.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to a starter for an engine such as an internal combustion engine and the object thereof is to produce an automatic drive or transmission therefor of novel and efficient construction and mode of operation.

My new construction of drive belongs to that general type as exemplified by patents heretofore issued to me such as Patent No. 1,125,935 dated January 26, 1915, and No. 1,274,370 dated August 6, 1918, according to which a driving member, whether the pinion 5 itself which engages the engine member such as the fly wheel or a separate member which controls such a pinion, is mounted on a rotatable shaft such as a screw shaft and automatically causes engagement of the drive 10 with and its disengagement from the engine member after the engine has started on its own power.

One of the main objects of my invention is to relieve the rotatable member or screw 15 shaft of the driving load and to place such load upon a separate shaft which may be directly or indirectly driven by the starting motor or other source of power, and on which the driving pinion may be rather 20 closely fitted instead of the necessarily loose fit if such pinion were mounted upon a screw shaft. Moreover my construction 25 enables the shifting mechanism to be made comparatively small and light and the actual driving parts to be made of any size according to the particular requirements as to 30 load or location.

My present invention relates more particularly to the construction of the driving 35 member which is provided with yielding driving means capable of absorbing the shock of impact of the teeth of such member with the fly wheel in case of end to end engagement and also capable of yieldingly 40 driving the engine member or fly wheel during the starting operation.

In the drawing the figure thereof is a sectional elevation of a starter embodying my invention.

Referring to the particular embodiment 50 of my invention, the same is selected as one

of various forms of which my invention may partake. Moreover, while I have shown the drive as direct-driven by the extended armature shaft of a motor, it will be understood that it may be indirectly driven and also while I have shown the so-called in-board type of drive, the other or outboard type may be employed.

As shown, the driving shaft 1 is the extended armature shaft of a starting motor indicated at A. To this shaft there is secured as by means of the key 2 a gear 3, the same being in the present instance located adjacent the motor. Upon this driving 60 shaft is mounted for longitudinal movement thereof and rotary movement therewith, a driving member of novel construction and constituting the subject matter of this invention. As shown, the driving member is composed of two main parts, to wit, a driving sleeve 4 fitting rather loosely upon the driving shaft and adapted to slide thereon. The outer or right hand end of this sleeve is enlarged to form a driving head, 65 and the same is provided at its extreme outer end with a gear 5. This gear which is formed separate or integral with the sleeve (but here formed separate) is a shroud gear inasmuch as the flanges 6 and 7 encompass 70 the gear, the flange 7 being here an annulus secured to the sleeve by the screws 8 which also serve to hold the gear 5 in place.

Upon the sleeve 4 the driving member proper is mounted, the same being here in 75 the form of a pinion 9 adapted to engage with the engine member such as with the teeth 10^a of the fly wheel 10. This pinion is operatively connected with the sleeve by a yielding driving connection which as shown 80 consists of a coiled driving spring 11 connected at one end to the sleeve head 4^a by the stud 12 and at the other end to the pinion by the stud 13. By reason of this construction the power or torque is transmitted 85 from the sleeve to the pinion in a yielding manner inasmuch as the drive is through the spring 11 and the pinion is capable of a rotary movement with respect to the sleeve, besides which it is capable of an independent 90 longitudinal motion with respect thereto which is yieldingly resisted by the spring, as hereinafter explained.

Suitable clutch means are provided for 95 the purpose of transmitting the power or torque from the driving shaft 1 to the sleeve 4 when the driving member is moved longi-

tudinally to the left into driving position. In the present instance such clutch means consists of clutch jaws 14 on the inner end of the sleeve 4 and complementary clutch jaws 15 on the outer end of the hub 3^a of the gear 3. As a result of this construction the torque or load is transmitted from the driving shaft 1, indirectly therefrom through the gear hub 3^a to the sleeve 4, 10 thence through the driving spring 11 to the pinion 9, and finally to the fly wheel.

Means for automatically controlling the driving member in its longitudinal movement for meshing with and demeshing from the fly wheel is mounted entirely extraneous 15 of the driving shaft and the driving member, and the same does not carry any of the driving load. In the present instance this shifting means is mounted on an axis parallel 20 to the longitudinal axis of the driving shaft 1.

As shown, the shifting means comprises essentially a rotatable shaft 16 and a control member or gear 17 mounted thereon. The 25 shaft 16 is mounted in suitable manner as in the bearings 18 and 19 supporting its outer ends and located in a casing or bracket 20. To the inner end of the shaft 16 there is secured in suitable manner, as by means of 30 the pin 21, a gear 22 in constant mesh with the gear 3, whereby the shafts 1 and 16 always rotate together. The shaft 16 has a screw-threaded portion 16^a on which the gear 17 is threaded, whereby when the shaft 35 is rotated this gear will be automatically advanced longitudinally to the left and also will be automatically retracted to its normal or disengaged position shown in the drawing when the engine starts on its own power 40 as hereinafter explained. This gear 17 is in constant mesh with the gear of the driving member and is operatively connected therewith in such manner that its longitudinal movements will be communicated to the 45 driving member in order to shift or slide the latter along the driving shaft 1.

Describing a cycle of operation and beginning with the parts in their normal position shown, the rotation of the motor and the 50 driving shaft will cause a rotation of the parallel or countershaft 16. As a result the gear 17 will be advanced longitudinally to the left carrying with it the driving member. The pinion thereof will now be brought into 55 mesh with the fly wheel and upon full mesh being obtained the clutch jaws 14 and 15 will engage and the driving member will thereupon be driven positively by the driving shaft through said clutch, the driving 60 sleeve, drive spring and pinion 9. When the engine starts on its own power the excess speed of rotation resulting therefrom will cause the automatic retracting movement of the gear 17 to the right along the screw 65 shaft, carrying the driving member in the

same direction and demeshing the pinion 9 from the fly wheel.

In the described driving operation the pinion 9 is adapted to yield rotarily according to the varying resistances presented by 70 the fly wheel, especially when the engine goes over the compression points. This yielding is due to the presence of the drive spring 11 which not only has the function of transmitting torque but the function of 75 yielding for the purpose stated.

In the event that the pinion teeth and the fly wheel teeth should abut end to end the pinion will become momentarily stopped in its longitudinal movement but the sleeve 4 80 will continue in its longitudinal movement against the compression action of the drive spring 11 which yields and permits of said relative movement between the pinion and the sleeve and thereby absorbs the shock of 85 this abutting condition. The pinion will thereupon rotate slightly so that its teeth will come into register with the fly wheel teeth, whereupon full mesh will be obtained.

The two sets of gearing represented by 90 the gears 3 and 22 in one set and 5 and 17 in the other set, have a certain relationship. These gears must be of the same diameter and number of teeth or else present the same gear reduction between their individual 95 members.

If desired suitable means may be employed for holding said longitudinally movable parts in their normal or disengaged position at the time when the shafts are still 100 rotating. In the present instance such means coöperate directly with the gear 17, the same consisting of a spring-pressed pin or rod 23 sliding transversely through the screw shaft and having a pair of lateral 105 arms 24 and 25 in which slides a latch 26. The pin is spring-pressed by means of the spring 27 and the latch by the spring 28. This device is speed-controlled inasmuch as when the screw shaft is rotating the pin 23 110 and its latch 26 will be thrown outwardly by centrifugal force in such position that said latch will engage behind the flange 29^a of a shell 29 secured to the gear 17. The purpose of this catch device is to hold the 115 gear 17 and consequently the driving member in retracted position during the time when the shafts may be still rotating so that the driving member will not tend to move toward or clash with the rotating fly wheel. 120 When the shafts and their associated parts come to rest the catch device will assume its normal position shown in the drawing in which the latch is disengaged from the shell.

125 I claim:

1. In an engine starter, a drive comprising a driving shaft, driving means mounted thereon for longitudinal movement thereof to engage a member of the engine to be 130

- started and for rotary movement therewith for rotating such engine member, such driving means including a yielding driving element, and shifting means mounted extraneous of such shaft and coöperating with the driving means to control the engaging and disengaging movements thereof. 6. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, a spring coiled around such sleeve and interposed between it and the driving member to drive the latter and also yieldingly resist its sliding movement on the sleeve, and shifting means mounted extraneous of such shaft and coöperating with the sleeve to control the engaging and disengaging movements of the shifting means. 7. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, a driving connection between the sleeve and the driving member, such sleeve having a gear portion, and shifting means mounted extraneous of such shaft, and including a longitudinally shifting gear in constant mesh with the gear portion of the sleeve and adapted to control the longitudinal movements thereof. 8. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, a driving connection between the sleeve and the driving member, such sleeve having a gear portion, and shifting means mounted extraneous of such shaft, and including a second shaft parallel with the driving shaft and driven thereby, and a gear longitudinally and automatically shiftable thereon by reason of their relative movements, such gear being arranged extraneous of such shaft and coöperating with the driving means to control the engaging and disengaging movements thereof. 2. In an engine starter, a drive comprising a driving shaft, driving means mounted thereon for longitudinal movement thereof to engage a member of the engine to be started and for rotary movement therewith for rotating such engine member, and also mounted for rotary movement with respect thereto, such driving means including a yielding driving element, and shifting means mounted extraneous of such shaft and coöperating with the driving means to control the engaging and disengaging movements thereof. 3. In an engine starter, a drive comprising a driving shaft, driving means mounted thereon for longitudinal movement thereof to engage a member of the engine to be started and for rotary movement therewith for rotating such engine member, such driving means including in its structure a spring driving connection, and shifting means mounted extraneous of such shaft and coöperating with the driving means to control the engaging and disengaging movements thereof. 4. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, a driving connection between the sleeve and the driving member, such sleeve having a gear portion, and shifting means mounted extraneous of such shaft, and including a longitudinally shifting gear in constant mesh with the gear portion of the sleeve and adapted to control the longitudinal movements thereof. 5. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, a driving connection between the sleeve and the driving member, such sleeve having a gear portion, and shifting means mounted extraneous of such shaft, and including a second shaft parallel with the driving shaft and driven thereby, and a gear longitudinally and automatically shiftable thereon by reason of their relative movements, such gear being arranged extraneous of such shaft and coöperating with the driving means to control the engaging and disengaging movements thereof. 10 15 20 25 30 35 40 45 50 55 60 65 70 75 80 85 90 95 100 105 110 115 120 125 130

ranged to mesh with said gear portion of the sleeve.

9. In an engine starter, a drive comprising a driving shaft, driving means mounted thereon for longitudinal movement thereof to engage a member of the engine to be started and for rotary movement therewith for rotating such engine member, such driving means including a sleeve slidable on the 10 shaft and adapted to be drivenly connected therewith upon its advance longitudinal movement, a driving member slidable on the sleeve and adapted to engage the engine member on such advance longitudinal 15 movement of the sleeve, a driving connection between the sleeve and the driving member, such sleeve having a gear portion, and shifting means mounted extraneous of such shaft, and including a second shaft 20 parallel with the driving shaft and driven thereby, such second shaft having a screw-threaded portion, and a gear threaded on such screw-threaded portion and arranged to mesh with said gear portion of the sleeve.

10. In an engine starter, a drive comprising a driving shaft, driving means mounted thereon for longitudinal movement thereof to engage a member of the engine to be started and for rotary movement therewith for rotating such engine member, such driving means including a sleeve slidable on the shaft and adapted to be drivenly connected therewith upon its advance longitudinal movement, a driving member slidable on the sleeve and adapted to engage the engine member on such advance longitudinal movement of the sleeve, such sleeve having an enlarged end forming a driving head and a gear portion, a drive spring connected at its ends respectively with the driving head and the driving member, and shifting means mounted extraneous of such shaft and including a longitudinally shifting gear in constant mesh with said gear portion and adapted to control the longitudinal movements thereof. 25 30 35 40 45

VINCENT BENDIX.
